ELECTRON DISCHARGE DEVICE

Terry M. Shrader, Landisville, Pa., assignor to Radio Corporation of America, a corporation of Delaware

Application April 5, 1956, Serial No. 576,395

The terminal fifteen years of the term of the patent to be granted has been disclaimed

10 Claims. (Cl. 315—39.63)

This invention relates to electron discharge devices, and more especially it relates to magnetrons.

A principal object of the invention is to provide a novel combination of cathode and grid structures for electron discharge tubes, particularly suited for use in magnetrons and the like.

Another object is to provide an improved magnetron having a series of discrete grid-controlled primary emitters which are especially shielded against back-bombardment by electrons.

Another object is to provide a grid-controlled magnetron having a series of discrete electron emitting cathode elements each housed in a respective anti-bombardment chamber, in conjunction with an individual grid for each cathode element also housed in the corresponding cathode compartment.

A feature of the invention relates to an electron discharge tube employing a series of discrete electron emitting cathodes each surrounded by a respective control grid, and with each cathode-grid combination being located within a respective recess in a common metal member, whereby all the cathodes and all the grids are shielded by said member against undesirable bombardment by high energy orbitally moving electrons.

A further feature relates to the novel organization, arrangement and relative location and interconnection of parts which by their mutual cooperation constitute an efficient high power grid-controlled electron tube, especially of the magnetron kind.

Other features and advantages will appear from the following descriptions and from the appended claims and attached drawing.

While the invention finds its primary utility as embodied in a magnetron tube, it will be clear that certain features of the invention can be equally well applied to other kinds of electron tubes.

Accordingly, in the drawing,

Fig. 1 is a side elevational view, partly sectional, of a magnetron embodying the invention. For clarity and simplicity in the drawing certain parts are omitted;

Fig. 2 is a broken sectional view of Fig. 1 taken along the line 2—2 thereof;

Fig. 3 is a detailed view of part of the cathode anchoring and tensioning means of Figs. 1 and 2;

Fig. 4 is a detailed view of one of the cathode-grid units of Figs. 1 and 2;

Fig. 5 is a schematic view of a magnetron embodying the invention.

As is well known, a magnetron usually comprises an electron emitting cathode surrounded by an anode which in one known kind of magnetron has a series of resonant cavities facing the cathode. By subjecting the electrons to a constant magnetic field transverse to the electron trajectories, the electrons are constrained to follow orbital or arcuate paths, and cooperate with the anode cavities to induce radio frequency voltages therein. A large percent of the emitted electrons leave the cathode in such a

2

phase that instead of giving energy to the radio frequency field, they absorb energy therefrom and return to the cathode. These latter electrons bombard the cathode with sufficient energy to cause undesirable effects, amongst which may be mentioned, useless dissipation of power at the cathode, destructive bombardment of the cathode surface, and ionization of the cathode material. These disadvantages are even more pronounced when it is attempted to modulate the intensity of the electron streams, for example, by the employment of an intervening control grid. Here again the back-moving electrons also bombard the grid, raising its temperature undesirably and even causing the grid to become a spurious emitter. The present invention provides a solution for the said difficulties, and permits of the construction of a high-powered magnetron either for pulsed oscillatory operation or for grid-modulated operation.

Referring to the drawing there are shown the cathode, grid and anode assembly of a magnetron. The cathode-grid unit is designated by the numeral 10, and the anode unit is designated by the numeral 11. Merely for purposes of clarity in the drawing, the usual evacuated envelope bulb or envelope of glass or other non-magnetic material is omitted from the drawing. Preferably, although not necessarily, the magnetron is of the water-cooled kind. The cathode assembly may include a tubular metal member 12 having a series of parallel longitudinal grooves or recesses 13 uniformly arranged around the external periphery thereof. In the particular tube illustrated, the member 12 has twelve such grooves.

Preferably, although not necessarily, each groove has a flat face 14 which extends approximately radially. The opposite wall of the groove, namely wall 15, is inclined at a suitable angle, for example sixty degrees, thus defining a somewhat V-shaped groove. If necessary each wall 14 may terminate in a flange 16 which extends short of the opposite wall 15 to define an electron emergence window 17 for each groove.

Suitably mounted in each groove in insulated space relation to the walls of the groove, is a cathode-grid unit. Each cathode of such unit may be in the form of an elongated flat metal ribbon or strip 18 and it may be surrounded by a respective foraminous or wire-wound control grid 19. Each cathode strip may be of the so-called directly heated kind, having its surface which faces the corresponding window 17 provided with a coating of any well known electron emissive material. If desired, each cathode element instead of being a flat ribbon, may be in the form of an elongated trough-like metal member 50 with the trough packed with thorium or similar electron emissive material, in which case the trough may be covered with a perforated or foraminous cover, thus providing what is known as a cathode of the dispenser kind.

Each of the cathode elements at its upper end is supported from a metal ring 20 which in turn is fastened to a main tubular metal support 21 for the multiple unit cathode-grid assembly. Ring 20 has a series of twelve arcuate slots 22 through which pass the upper ends of the respective cathode elements. For the purpose of anchoring each cathode element so as to prevent it changing its planar relation with respect to its associated grid, the upper face of ring 20 is slightly undercut to provide oppositely disposed recesses into which fit the T-shaped tabs or lugs 23 on the respective cathode element.

Insulatingly attached to ring 20 by suitable bolts 24 is another metal ring 25. The two rings are insulated from each other by suitable insulating bushings 26, and insulating washers 27. The outer margin of ring 25 is of greater thickness than the inner margin and the latter is provided with a series of apertures 28 in alignment with the slots 22 to permit the passage of the respective cath-

ode elements. These apertures 28 have fitted therein, respective bushings 29, the lower ends of which abut against the upper end of member 12.

The lower end of each cathode element passes through an opening in a respective flexible cathode tensioning support 30. The lower face of that support has a pair of aligned grooves to receive the T-shaped head or lug 31 on the lower end of the cathode element. The flexible supports 30 are fastened to a metal ring 32 which is spaced from member 12 by a plurality of bushings 33 mounted in respective apertures in ring 32. The cathode elements are held under appropriate longitudinal tension by the respective leaf springs 34 which bear against the members 30 urging the latter in a downward direction.

Brazed or otherwise joined to the upper end of member 12 is a metal ring 35 also having a series of openings into which are fitted the respective bushings 29. The outer margin of ring 35 has a flange which is brazed or otherwise joined to the ring 25. Similarly brazed or joined to the lower end of member 12 is a metal ring 36 having openings into which are fitted the bushings 33. The flange 37 on the outer margin of ring 36 is brazed to ring 32. The elements 25, 35, 12, 29 at their respective contacting surfaces are brazed to form fluid-tight joints, as is also true of the elements 32, 36, 12, 33.

The inner opening of ring 32 is closed by a cup-shaped closure member 38 which is concentrically telescoped within member 12. The space between member 12 and rings 25 and 32 is divided into two parts by a tubular partition 39 and a cooperating pair of annular partitions 40, 41 fastened to the respective ends of member 39. The members 40, 41 have respective aligned apertures through which the respective bushings 29, 33 extend.

The upper end of member 39 adjacent to ring 25 is connected by means of an intermediate ring 42 to an inner fluid supply pipe 43 extending coaxially through the main support 21, and the central opening in ring 25 being connected to an outer pipe 44 which extends coaxially between pipe 43 and member 21. Thus as indicated by the arrows, there is provided a continuous path for the passage of a cooling fluid in contact with the heated portion of the various parts, but of course without touching the cathode elements which are located outside the fluid passage.

Each of the grid electrodes 19 may comprise a pair 45 of rigid metal side rods 45, 46 (see Fig. 4) around which is wound and anchored thereto a helical fine wire 47 to constitute the grid laterals. It will be understood, of course, that any other known construction for the grids may be employed. In order to support and insulate each grid from its associated cathode element, there is attached in any suitable manner to the ring 20 an insulator ring 48 which may be of ceramic and into which the upper ends of the various grid side-rods extend. Similarly attached to ring 32 is another metal ring 49 into which the lower ends of the various grid side-rods extend and to which they may be welded or otherwise suitably fastened so as to connect all the grids in parallel electrically. A suitable lead-in member 50 can be connected to ring 49, which ring is insulated in any suitable manner, for example by ceramic ring 51, from ring 32. It will be understood, of course, that any other suitable support means may be employed for insulatingly supporting the grids in their respective grooves in spaced relation to the respective cathode elements.

The various filament tensioning members 30 can be connected in parallel by attaching the filament supports 30 to a metal cap member 52. The lower end of the cathode grid assembly 19 can be closed by the cup-shaped metal cap 52 which may serve to connect the several members 30 in parallel. A similar cup-shaped metal member 53 closes off the upper end of the assembly 19. It will be observed that the member 53 has a central opening which is of larger diameter than the outer diameter 21, so that member 21 is conductively connected through

ring 20 only to the upper ends of the cathodes 18. As shown in the schematic diagram of Fig. 5, the current for heating the various cathode elements can be connected over supply conductors (not shown) but connected to the members 21 and 44. A suitable probe or small pick-up loop 54 can be insulatingly sealed through the wall of the evacuated enclosing bulb or container 55 and provided with a conventional coaxial connector 56. The grid connection ring 49 can be connected to a suitable lead-in 57. In use, the device is located between the pole-pieces 58, 59 of a magnet for subjecting the electrons between the cathodes and the anode block to a magnetic field to cause the electrons to follow the desired orbital or arcuate paths.

Since the operation of magnetron devices is well known, suffice it to say that when the various cathode elements are raised to electron emitting temperature they emit electrons in a direction which would normally be toward the inclined face 15 of each groove. However, because of the steady positive potential applied to the anode block 11, the electrons emerge through the respective windows 17 and would ordinarily move in somewhat linear trajectories towards the anode. However, when they are subjected to the magnetic field from the pole-pieces 58, 59, they execute orbital or arcuate movements. One typical such path of movement is indicated by the dotted line in Fig. 2. The electrical and dimensional parameters are chosen so that as many of these orbital electrons as possible induce high frequency currents in the associated resonant cavities formed by adjacent ribs. By reason of the construction hereinabove described, the electrons are prevented from bombarding the cathodes and grids in the successive grooves. If desired, the walls of each groove may be treated in any well known manner to reduce the likelihood of secondary electron emission therefrom.

Various changes and modifications may be made in the disclosed embodiment without departing from the spirit and scope of the invention.

What is claimed is:

1. A magnetron comprising a plurality of discrete electron emitting cathodes, a corresponding plurality of discrete grids one for each cathode, generally circular anode means for said grids and cathodes and surrounding them in spaced relation, a shield for all said cathodes and grids, said shield having a plurality of discrete recesses in each of which is insulatingly mounted a corresponding cathode and grid with the cathode oriented therein so as normally to emit electrons in the space between the cathodes and anode means, each of said recesses in said shield defining an electron emergence window facing the anode and the walls of each recess being oriented to shield both the cathode and grid therein from electron bombardment.
2. A magnetron according to claim 1 in which said cathodes are oriented so as normally to emit electrons in a non-radial direction with respect to said anode means.
3. A high powered electron tube, comprising an enclosing evacuated envelope, a generally circular metal body having a plurality of elongated recesses symmetrically arranged around its periphery, an electron emitting cathode and a grid electrode in each recess, and means to support each cathode and grid in each recess with such orientation that the cathode normally tends to emit electrons in a non-radial direction with respect to said metal body, and anode means surrounding said cathodes and grids in spaced relation thereto.

4. A high powered electron tube according to claim 3, in which each of said recesses has a plurality of flat side walls and each cathode has a substantially planar emitting surface substantially facing one side wall of the recess in which it is mounted, each recess having an electron emergence window facing said anode means.

5. A high powered electron tube according to claim 4, in which the opposite side walls of each recess has a flange to define a secondary recess within which the cathode and grid are located.

5

6. A high powered electron tube according to claim 5, in which each cathode is in the form of a flat metal strip and is insulatingly mounted within its respective recess in said metal body so that its plane is substantially radial with respect to said anode means.

7. A magnetron comprising a plurality of discrete elongated cathode elements, a plurality of grid electrodes one for each cathode element, a shield member having a plurality of elongated grooves in its external surface and within each of which is mounted a corresponding cathode and grid, anode means surrounding said cathodes and grids, means for providing a magnetic field parallel to said cathode elements to cause electrons emitted by said cathode elements to follow arcuate paths in the space between said cathode elements and said anode means, and means including the walls of said grooves for shielding each cathode and grid from electron bombardment by electrons returning to said cathode elements and grid electrodes along said arcuate paths.

8. A magnetron comprising a hollow anode, a cathode grid assembly mounted within said anode and comprising a plurality of discrete cathode elements, a corresponding plurality of grid electrodes one for each cathode element, a single support member having a plurality of discrete recesses, and means insulatingly supporting each cathode and grid within a respective recess.

9. An electron discharge device comprising a plurality of discrete electron emitting cathodes, a corresponding plurality of discrete grids one for each cathode, anode means for said grids and cathodes and surrounding them in spaced relation, a shield for all said cathodes and grids, said shield having a plurality of discrete recesses

in each of which is insulatingly mounted a corresponding cathode and grid with the cathode oriented therein so as normally to emit electrons in the space between the cathodes and anode means, each of said recesses in said shield defining an electron emergence window facing the anode and the walls of each recess being oriented to shield both the cathode and grid therein from electron bombardment, each of said cathodes is in the form of an elongated member having an electron emissive surface facing a side wall of the recess in which it is located.

10 facing a side wall of the recess in which it is mounted.

10. An electron discharge device comprising a plurality of discrete electron emitting cathodes, a corresponding plurality of discrete grids one for each cathode, anode means for said grids and cathodes and surrounding them in spaced relation, a shield for all said cathodes and grids, said shield having a plurality of discrete recesses in each of which is insulatingly mounted a corresponding cathode and grid with the cathode oriented therein so as normally to emit electrons in the space between the cathodes and anode means, each of said recesses in said shield defining an electron emergence window facing the anode and the walls of each recess being oriented to shield both the cathode and grid therein from electron bombardment, each of said recesses is in the form of an elongated groove having side walls, and each of said cathodes is in the form of a metal strip carrying an electron emissive surface facing one side wall of its recess.
